(57) CLAIM

The ornamental design for an expandable connector for shelter, as shown and described.

DESCRIPTION

FIG. 1 is a front perspective view of a first embodiment of the expandable connector for shelter in the expanded configuration.

FIG. 2 is a front view of a first embodiment of the expandable connector for shelter in the expanded configuration.

FIG. 3 is a back view of a first embodiment of the expandable connector for shelter in the expanded configuration.

FIG. 4 is a left side view of a first embodiment of the expandable connector for shelter in the expanded configuration.

FIG. 5 is a right side view of a first embodiment of the expandable connector for shelter in the expanded configuration.

FIG. 6 is a top view of a first embodiment of the expandable connector for shelter in the expanded configuration.

FIG. 7 is a bottom view of a first embodiment of the expandable connector for shelter in the expanded configuration.

FIG. 8 is a front perspective view of a first embodiment of the expandable connector for shelter in the collapsed configuration.

FIG. 9 is a front view of a first embodiment of the expandable connector for shelter in the collapsed configuration.

FIG. 10 is a back view of a first embodiment of the expandable connector for shelter in the collapsed configuration.

FIG. 11 is a left side view of a first embodiment of the expandable connector for shelter in the collapsed configuration.

FIG. 12 is a right side view of a first embodiment of the expandable connector for shelter in the collapsed configuration.

FIG. 13 is a top view of a first embodiment of the expandable connector for shelter in the collapsed configuration.

FIG. 14 is a bottom view of a first embodiment of the expandable connector for shelter in the collapsed configuration; and,

FIG. 15 is a left side view of a first embodiment of the expandable connector for shelter in the expanded configuration connecting two adjacent shelter structures.

The broken lines in the figures showing shelter structures depict environment only that forms no part of the claimed design.
